UNITED STATES PATENT OFFICE.

ALBERT J. CHAMPION, OF FLINT, MICHIGAN, ASSIGNOR TO CHAMPION IGNITION COMPANY, OF FLINT, MICHIGAN, A CORPORATION OF MICHIGAN.

SPARK-PLUG.

1,338,674.

Specification of Letters Patent.

Patented May 4, 1920.

Application filed November 30, 1917. Serial No. 204,568.

To all whom it may concern:

Be it known that I, ALBERT J. CHAMPION, a citizen of the Republic of France, residing at Flint, in the county of Genesee and 5 State of Michigan, have invented certain new and useful Improvements in Spark-Plugs, of which the following is a specification, reference being had therein to the accompanying drawings.

10 The invention relates to spark-plugs more particularly designed for use in connection with high-speed internal combustion engines and has for its object the protection of the electrodes and insulator and avoidance of pre-ignition.

In the drawing, my improved plug is shown in sectional elevation.

A is the casing of the plug having the usual threaded nipple B, C is the insulator 20 within the casing, D is the insulated electrode and E the grounded electrode. It is the primary object of the invention to protect the insulator and the electrode carried thereby from the intense heat. At the same 25 time it is essential to avoid short-circuiting by the sooting of the insulator and also to avoid retention of flame or slowly burning gas which would cause pre-ignition. Heretofore various constructions have been 30 devised in which the insulator is shielded from the heat, but with such constructions there is, first, the danger of short-circuiting through carbon deposit upon the cooler portions of the insulator surface, and sec- 35 ond, the danger that the space beyond the shield will entrap combustible gas which by reason of its proximity to the cooled walls will burn slowly and therefore will cause pre-ignition of a subsequently intro- 40 duced gaseous charge.

With the present construction these difficulties are overcome by so fashioning the insulator and the casing that the contour of the one will conform to that of the other 45 but with sufficient separation to maintain the insulation. The fact that the two surfaces are uniformly spaced from each other reduces the volume of this space to the minimum without any reduction in the insulating properties. Furthermore the uni-

formly narrow space between the walls will prevent ignition of the gas therebetween.

At the end of the insulator adjacent to the electrode the casing is cut away so as to leave an annular portion F exposed to 55 the flame. The heat of the flame is sufficient to burn off any soot deposit, but the area of the surface which is thus exposed is so small that the heat communicated to the insulator may be readily dissipated as well 60 as the heat which is communicated to the electrode. As specifically shown the insulator is seated in the casing upon a gasket G upon the shoulder H, and the portion I projecting inward therefrom is of slightly 65 tapering section and rounded at its inner end. This portion is within the threaded nipple portion B of the casing, the walls of which are cooled by contact with the water jacket of the engine, and as shown 70 the contour J of these walls is parallel to the contour of the insulator and but slightly spaced therefrom. This will form a portion K at the inner end which projects inwardly to partially shield the end of the 75 insulator, leaving only the small annular exposed portion F, and the inner end of the casing has the flaring mouth L within which are arranged the electrodes D and E.

In operation, when the explosive charge 80 is compressed only a relatively small volume of the gas can be forced into the restricted space between the insulator and the surrounding walls of the casing. This slight volume of gas will be expelled during the expansion stroke, and any remnant 85 retained in the narrow space cannot be ignited on account of the close proximity of the cooled surfaces. At the same time there is an extended insulating surface between 90 the electrode and the point of contact of the insulator upon the casing, while the annular portion immediately adjacent to the electrode is cleared from any soot deposit by exposure to the flame. 95

What I claim as my invention is:

In a spark plug, the combination with an insulator and an electrode extending longitudinally therethrough, of a casing in which said insulator is seated, having a 100

threaded nipple portion inside of the seat corresponding in contour with the portion of said insulator inside of the seat and uniformly spaced therefrom a restricted distance to prevent ignition of any gases therebetween, said nipple portion extending partly around the inner end of said insulator and having a flaring mouth with an

opening surrounding said electrode, and a second electrode extending transversely of 10 the first-mentioned electrode and adjacent thereto, said second electrode having its opposite ends engaging the wall of the flaring mouth.

In testimony whereof I affix my signature. 15
ALBERT J. CHAMPION.
